WIRE HOLDER FOR USE WITH CYLINDRICAL CONTAINERS

Charles Marner, Chicago, Ill., assignor to Nachman Corporation, Chicago, Ill., a corporation of Illinois

Application July 28, 1955, Serial No. 37,189

Term of patent 3½ years

(Cl. D58—26)

FIG. 1

FIG. 2

FIG. 3

Figure 1 is a side elevational view of a wire holder for use with cylindrical containers, showing my new design;

Figure 2 is an end view thereof taken on a reduced scale;

Figure 3 is a perspective view thereof, showing the handle detached from the carton, and taken on a reduced scale.

I claim:

The ornamental design for a wire holder for use with cylindrical containers, as shown.
